UNITED STATES PATENT OFFICE.

FRANK J. GILROY, OF BUFFALO, NEW YORK.

LOCOMOTIVE-FEED-WATER HEATER.

1,050,451.

Specification of Letters Patent. Patented Jan. 14, 1913.

Application filed October 9, 1912. Serial No. 724,694.

To all whom it may concern:

Be it known that I, FRANK J. GILROY, a citizen of the United States, residing at Buffalo, in the county of Erie and State of New York, have invented certain new and useful Improvements in Locomotive-Feed-Water Heaters, of which the following is a specification, reference being had therein to the accompanying drawing.

10 This invention relates to "front end" feed water heaters for locomotives, and the general object is to provide simple, inexpensive, and effective heating devices which utilize the heat of the exhaust steam from the cylinders and which can be readily applied to old or new engines and can be thrown into or out of action by mechanism at the cab. The water to be heated is forced through a heating jacket on the smoke box and thence 15 into the boiler and is heated in transit slightly by the wall of the smoke box and largely by the exhaust steam passed through a series of tubes in the water jacket.

In the accompanying drawings, Figure 1 20 is a partly diagrammatic side view of a boiler and smoke box provided with my devices, parts being omitted. Fig. 2 is an enlarged front sectional view of the smoke box containing and carrying most of the novel 25 devices. Fig. 3 is a side view on a larger scale showing the water jacket in place, the outer part of the jacket being removed and parts being broken away. Fig. 4 is a sectional view showing a valve for directing the 30 exhaust steam from the engine cylinders. Fig. 5 is a section on the line 5--5, Fig. 4.

In these figures, A represents a common 35 type of locomotive boiler, A' the smoke box having the usual stack A² with a funnel shaped intake, and A³ the exhaust passages from the engine cylinders. Upon each side of the upper portion of the smoke box is placed a sort of hollow jacket member A⁴, Fig. 1, formed by a metal frame externally 40 covered by metal plates B B' concentric with the smoke box. Each frame, the two being exactly similar, preferably extends from end to end of the smoke box and has approximately parallel front and rear sides 45 or bars B², B³ connected at their ends by bars B⁴, B⁵ and further connected by bars B⁶, B⁷ at a short distance from the bars B⁴, B⁵ respectively, the frame being thereby divided to form a large central compartment with 50 narrow compartments above and below it,

respectively. The plate B' forms a continuation of the plate B although preferably distinct therefrom as shown. Both plates are secured to the frame by bolts and the frame itself is similarly secured to the smoke box 60 wall, all joints being made fluid tight, preferably by the use of copper gaskets or plates. The bars B⁶, B⁷ serve as headers for a series of curved steam tubes B⁸ midway between the plate B and the smoke box wall and connecting the lower and upper narrow compartments B⁹, B¹⁰ and passing through the larger compartments B¹¹, Fig. 2. Water is forced into each compartment B¹¹ by a pump C and a pipe C' on each side of the boiler, 70 and passes from the compartment to the boiler through a pipe C².

Exhaust steam from the engine cylinders enters the smoke box at A², as usual, directly below the stack, but in this case passes first 75 into a cylindrical valve casing D containing an oscillating, cylindrical-segment valve D' which may, at will, be made to close either a vertical discharge passage D² or a lateral passage D³, the steam in the former case 80 passing through a discharge passage D⁴ and thence upward across the interior of the smoke box to the stack A², and in the latter case into the broad curved conduit D² to one of the narrow upper steam compartments B¹⁰. From that compartment it 85 passes down through the pipes B¹¹ to one of the lower steam compartments B⁹, again crosses the smoke box in a similar flat conduit E to the other compartment B⁹, passes 90 upward through the pipes B¹¹ to the other upper steam compartment B¹⁰, and thence downwardly through a similar broad conduit E' which discharges, just above the valve D', into the passage D².

It will be observed that, the exhaust steam receives further heat while in the pipe D², gives up heat to the water while passing downwardly in the pipes B¹¹, is reheated in the conduit E, imparts heat to the water 100 while passing upward in the second set of pipes B¹¹, and is further heated in passing through the conduit E', so that in any case it is finally discharged with all the force desirable.

To equalize pressure and heat conditions in the heaters, they are connected near the upper sides of the water chambers by one or more pipes F.

The valve is operated by an arm D' fixed 110

to its shaft and yieldingly held in either one or the other of its two positions by suitable means, in this instance shown as a weight D³ borne by the arm. A rod D⁹ is pivotally connected to the arm's free end which passes out through the wall and jacket through a tube D¹⁰, packed to serve as a gland. This rod is reciprocated by the engineer in his cab by means of devices not here shown but 10 to be made the subject matter of a separate application.

The lower sides of each of the lower compartments of the jacket sections are so inclined that in the water chambers water may 15 tend to move forwardly to blow-off cocks G, while in the steam chambers it may tend rearwardly to valved drainage pipes G' leading to the receptacles G² from which the pump draws the water which is supplied to 20 the jacket sections.

As the lower steam chamber is narrow, its lower bar or wall is provided with an opening or openings H alining with the end portions of the small tubes and closed by a 25 removable plate H', and thereby ready access may be had to these tubes.

It may be noted that this apparatus when installed interferes with no steam pipes or other parts as ordinarily located within the 30 smoke box, that it may be readily thrown into or out of action at any moment, that water supplied by it to the boiler is always taken from the hottest part of the apparatus, and that by means of the jacket sections and 35 the cross conduits waste heat is taken from practically every part of the gases entering the smoke box.

What I claim is:

1. The combination with the smoke box 40 of a locomotive, of a water heating jacket concentric with the smoke box wall, contiguous thereto, and provided with steam conduits for heating water therein, means for at will forcing water through said jacket 45 to the boiler, and means for at will causing exhaust steam to pass through said conduits.

2. The combination with the smoke box 50 of a locomotive, of a water heating jacket secured to the exterior of the smoke box and provided with internal steam conduits, means for forcing water through said jacket to the boiler, and means for at will causing 55 exhaust steam from the engine cylinders to pass through said conduits.

3. The combination with the smoke box 60 of a locomotive, of a heating jacket secured to the exterior of the smoke box and consisting of right and left side sections each provided with internal steam tubes, means 65 for at will directing water through said sections to the boiler, and means for at will di-

recting exhaust steam through said tubes and thence to the smoke stack.

4. The combination with a boiler and the smoke box of a locomotive, of a heating 65 jacket conforming to the wall of the smoke box, secured thereto, and consisting of distinct right and left sections, means for forcing water through each section and thence to the boiler, and means for at will directing 70 exhaust steam through said sections in succession and thence to the stack.

5. In a locomotive, the combination with the boiler and smoke box, of a water heating jacket conforming and secured to the wall 75 of the smoke box and consisting of distinct right and left side sections each having an internal series of steam tubes, means for forcing water through said sections to the boiler, a pipe for conveying exhaust steam 80 from the engine cylinders to the tubes of one of said sections, a pipe for conveying the steam from the first set of tubes to the tubes of the other section, a pipe for conveying steam from the tubes last mentioned 85 to the stack, and a manually controlled valve governing the admission of steam to the pipe first mentioned.

6. The combination with a locomotive, of a water heating jacket provided with steam 90 tubes and removably secured to the walls of the smoke box, means for forcing water through the jacket to the boiler, a conduit leading from the exhaust passages to one side of the jacket to supply steam to the 95 tubes therein, a conduit leading from one side of the jacket to the other side of the same, a conduit leading from the tubes at the other side of the jacket to an exhaust passage below the stack, and a manually 100 operable valve controlling the passage of steam through said conduits and tubes.

7. In a locomotive having a front end smoke box and passages for discharging exhaust steam therein below the stack, the combination with an external water jacket 105 mounted upon the smoke box and provided with internal steam tubes, means for forcing water through said jacket to the boiler, pipes for conveying steam from said passage to 110 said tubes and returning it to said passage at a point below the normal discharge opening therefor, and a manually actuated valve for at will allowing the steam to pass directly to said opening or diverting it into 115 said pipes.

In testimony whereof I affix my signature in presence of two witnesses.

FRANK J. GILROY.
